ILLUMINATED GLOBE MOUNTING

Raymond R. Dupler, Toledo, Ohio

Application January 3, 1938, Serial No. 182,933

9 Claims. (Cl. 240—2)

This invention relates to mountings for globes of glass or other translucent material and an object is to produce a simple and efficient mounting which enables the globe having diametrically opposed supports to be rocked or tilted in such manner as to afford removal of the globe therefrom without disturbing to any extent the lamp extending inside of the globe for illuminating same, the mounting being such as to permit the globe to be rotated about its axis and compensate for irregularities in the globe structure so that the globe can freely rotate.

Other objects will hereinafter appear and for purposes of illustration an embodiment of the invention is shown on the accompanying drawing in which:

Figure 1 is a side elevation of an illuminated globe mounting, portions being broken away to show the diametrically opposed supports;

Figure 2 is a perspective view of the supporting disc and lamp bracket;

Figure 3 is a side elevation of the supporting post, showing the disc in section and indicating by dotted lines the rocking action of the disc;

Figure 4 is a side elevation partly in section of an alternate mounting for the lower end of the globe.

The illustrated embodiment of the invention comprises a mounting for an illuminated globe comprising a base 10 to which is fixed a semi-circular bracket 11 formed with guide members 12 to support an annulus or meridian ring 13 which is slidable therein. Arranged within the ring 13 is a sphere or globe 14 of glass or other suitable translucent material. Formed in the lower portion of the globe 14 is an annular opening over the edge of which fits a grommet 15.

The lower end portion of the globe 14 is supported by a circular plate or disc 16 formed with an outwardly extending annular flange or ledge 17 at the lower edge. The disc has a nice fit within the opening and the outer side of the globe rests against the flange 17. In the central portion of the disc 16 is an opening 18 the upper portion of which flares outwardly as indicated at 19. Extending through the opening 18 in the disc is a post 20, the lower end of which is formed with a slot 21 fitting over the ring 13 to which it is fixed as by a press fit, rivet or other suitable securing means. Carried on the upper end of the post 20 by suitable legs is a lamp bracket and switch 22 to which an elongate lamp 23 is attached in the usual manner. For operating the switch a flexible pull cord 24 extends downwardly

from the switch 22 through an opening 25 in the disc 16, the lower portion being accessible near the base 10 so that the lamp can be switched on or off as desired. Wires 26 pass through an opening in the side of the post 20 and extend upwardly through the hollow bore thereof to the switch 22.

A collar 27 is fixed to the upper end of the post and is applied after the disc 16 is mounted in position, an annular flange 28 below the collar 27 providing a seat for the disc 16. The portion of the post between the flange 28 and the collar 27 is inwardly and outwardly curved as indicated at 29 on Figure 3 thereby providing substantially a ball and socket joint. This enables the plate 16 to tilt in any direction as indicated by the dotted lines on Figure 3, the fit between the plate and the post affording relatively free rocking motion and the outwardly flared portion on the disc affording sufficient clearance for this purpose. It will be noted that the rounded surface 19 on the post affords this rocking action without undesirable lost motion or play between these parts. Turning of the disc 16 relatively to the post is prevented by a pin 29 inclining upwardly and outwardly from the post into a notch 30 in the disc. The fit between the pin and the notch is such that rocking or tilting of the disc 16 is permitted but substantial turning movement is prevented.

The upper end of the globe 14 is releasably supported for rotation by a spring-pressed plunger 31 which is carried in any suitable manner by the globe and projects into a socket opening 32 in the ring 13. A smaller opening 33 in the outer portion of the ring 13 communicates with the socket 32 so that by inserting a nail or some sharp pointed instrument, the pin 31 can be pushed inwardly to free the globe from the ring 13. Thereupon, the globe 14 can be rocked with the disc 16 sufficiently to enable the globe to be lifted outwardly over the lamp 23. The opening defined by the grommet 15 should be of sufficient size so that it can be slipped over the lamp.

In the form shown in Figure 4, the grommet 15a has an inward extension 34 which seats against the disc 16a. Instead of the lamp bracket being carried by the post as in the above described construction, the lamp bracket and switch 22a are supported by legs 35 upon the disc 16a to which they are secured by screws 36. In this manner, the lamp tilts or rocks with the disc and facilitates the assembly of the globe 14a. The post 20a is substantially the same in construction so far as the mounting of the disc 16a is concerned, as above described. Likewise the pull cord 24

24a passes through an opening in the disc 16a. If desired, the disc 16a may be provided with a ledge as described in connection with Figures 1 to 3.

5 From the above description, it will be apparent that I have provided an exceedingly simple and inexpensive illuminated globe mounting by which the globe can be freely rotated. In the event that the axis of the opening defined by the grommet 15 or 16a is not properly aligned with the spring-pressed pin 31, the disc can rock or tilt in order to compensate for such irregularity. It will further be apparent that the globe can be mounted in position or rocked without difficulty, it being necessary merely to release the upper end of the globe 10 as above described and then rock the globe laterally in order to free the upper end of the globe from the ring and then by an outward motion, the globe may be moved free from the lamp 23.

It is to be understood that numerous changes 20 in details of construction, arrangement and operation may be effected without departing from the spirit of the invention especially as defined in the appended claims.

What I claim is:

25 1. A mounting for an illuminated globe comprising a base, an arcuate frame on the base, diametrically opposed supports on the frame, a globe carried by said supports, one support comprising a releasable member, the other support comprising a plate against which the globe rests, mounting for said plate enabling tilting movements in all directions, a lamp inside of the globe, and means to support said lamp.

30 2. A mounting for an illuminated globe comprising a base, an arcuate frame on the base, diametrically opposed supports on the frame, a globe carried by said supports, one support comprising a releasable member, the other support comprising a post carried by said frame, a lamp support carried by said post and projecting inside of the globe, a plate on which said globe rests adjacent the peripheral surface thereof, and a connection between said plate and post enabling free rocking movements of said plate in all directions.

35 3. A mounting for an illuminated globe comprising a base, an arcuate frame on the base, diametrically opposed supports on the frame, a globe carried by said supports, one support comprising a releasable member, the other support comprising a plate against which the globe rests, said plate having an aperture, a substantially hour glass shaped supporting member carried by said frame and projecting into said aperture and constructed and arranged to afford rocking movement of the globe, a lamp extending inside of said globe, and means for supporting said lamp.

40 4. A mounting for an illuminated globe comprising a base, an arcuate frame on the base, diametrically opposed supports on the frame, a globe carried by said supports, one support comprising a releasable member, the other support including an apertured plate against which the globe rests, a member carried by said frame and extending freely through said aperture and shaped to enable rocking movements of the plate relatively thereto, means for holding said plate against substantial turning movements with respect to said last named member, and a lamp 45 bracket disposed inside said globe and carried by the said other support.

5 5. A mounting for an illuminated globe comprising a base, an arcuate frame on the base, diametrically opposed supports on the frame, a globe carried by said supports and having an opening therein, one support comprising a releasable member arranged in diametrically opposed relation to said opening, the other support comprising a plate substantially fitting said opening, said plate having a central aperture provided with an outwardly flared rim, a post fixed at 10 its lower end to said frame and extending freely through the aperture in said plate, a lamp within said globe, a mounting for said lamp, and a reduced portion on said post forming a supporting shoulder for said plate and enabling tilting movements of the plate to facilitate removal of the globe.

6. A mounting for an illuminated globe comprising a base, substantially diametrically opposed supports on the base, one support including a releasable member and the other support including a movable globe sustaining member, means to mount said movable globe sustaining member for oscillatory movements in a plurality of planes angularly disposed with respect to each other and to the axis of the globe, a lamp, and means to support the lamp within the globe so that the latter can be removed while the lamp remains in position.

7. A mounting for an illuminated globe comprising a base, substantially diametrically opposed supports on the base, one support including a releasable member, and the other support including a movable globe sustaining member having an opening therein, the wall defining said opening being tapered, said last support further including means extending through said opening and having a lamp disposed within the globe, said lamp carrying means being provided with a circumferential groove, the wall defining said groove 35 being tapered to cooperate with the tapered wall 40 of the opening so that the globe sustaining member will tilt in all directions with respect to said lamp carrying means.

8. A device of the character described, including a base, a pair of diametrically opposed supports on the base, one of the supports including releasable means, a globe having an opening therein, the wall defining the opening being shouldered to maintain the globe in position with relation to the other of said supports, a globe sustaining member rockable in all directions, carried by the said other support and fitting within the opening, and engaging its said shoulder, a lamp, and means to support the lamp within the globe so that the latter can be removed while the lamp remains in position.

9. A mounting for an illuminated globe comprising a base, substantially diametrically opposed supports on the base, one support including a releasable member, and the other support including a globe sustaining member, means to movably connect the globe sustaining member to the last named support for movements in all directions with respect to the latter, a lamp, and means to support the lamp within the globe so that the latter can be removed while the lamp remains in position.
